Primary Examiner — Jason Daniel Prone*(74) Attorney, Agent, or Firm* — Haverstock & Owens LLP(57) **ABSTRACT**

A utility knife includes a body with a knife blade storable within the body and one or more magnets coupled to the knife body. The magnets are able to be embedded within the body or embedded with an adapter that is configured to removably couple with the utility knife. In some embodiments, the knife blade folds out from a side of the body and into an operable position. Alternatively, in some embodiments, the knife blade slides out of a top of the body and into the operable position. The utility knife is able to magnetically couple with a base having a magnetically attractable surface. The utility knife is securable to the base in a vertical orientation and a horizontal orientation.

MAGNETIC UTILITY KNIFE AND HOLDER**RELATED APPLICATION(S)**

This Patent Application claims priority under 35 U.S.C. 119(e) of the co-pending U.S. Provisional Patent Application Ser. No. 61/819,278, filed May 3, 2013, and entitled "MAGNETIC UTILITY KNIFE AND HOLDER." The Provisional Patent Application Ser. No. 61/819,278, filed May 3, 2013, and entitled "MAGNETIC UTILITY KNIFE AND HOLDER" is also hereby incorporated by reference.

FIELD OF THE INVENTION

This invention relates generally to items incorporating magnets. More particularly, this invention relates to a hand tool comprising magnets and a holder for magnetically securing the hand tool.

BACKGROUND OF THE INVENTION

Small tools including, tape measures, levels, pliers, screw drivers, wrenches, utility knives and others are an integral part of the professional and amateur tool kit. In particular, many projects require multiple tools to be used interchangeably throughout the course of the project. Tools not being used are typically placed on a tool bench or table and near the user for later use. However, because the tools are not secured, they may roll off of the tool bench or table and away from the user. Consequently, the user must stop what they are doing to look for the tools and take their eyes away from the project. This often leads to inefficiencies and time delays as the user must look for the proper tool and then focus back on the project in front of them.

SUMMARY OF THE INVENTION

A utility knife comprises a body with a knife blade storable within the body and one or more magnets coupled to the knife body. The magnets are able to be embedded within the body or embedded with an adapter that is configured to removably couple with the utility knife. In some embodiments, the knife blade folds out from a side of the body and into an operable position. Alternatively, in some embodiments, the knife blade slides out of a top of the body and into the operable position. The utility knife is able to magnetically couple with a base comprising a magnetically attractive surface. In some embodiments, the utility knife is secured to the base in a vertical orientation. Alternatively, in some embodiments, the utility knife is secured to the base in a horizontal orientation.

In one aspect, a utility knife comprises a body, a knife blade storable within the body, and one or more magnets coupled to the body. In some embodiments, the one or more magnets are embedded within and raised from an exterior of the body. In further embodiments, the one or more magnets are embedded within an adapter that removably couples with the body. In some embodiments, the knife blade folds out from a side of the body and into an operable position. In further embodiments, the blade slides out from a top of the body and into an operable position. In some embodiments, a shape of the one or more magnets is selected from a set comprising a strip, a ball bearing and a disc. In further embodiments, at least one of the one or more magnets comprise one or more of a neodymium magnet and a ceramic magnet. In some embodiments, the one or more magnets are configured with interlocking geometry in order

to removably couple with an interlocking base. In further embodiments, the one or more magnets are embedded within a raised surface of the body.

In another aspect, a system for securing a utility knife comprises a utility knife comprising a body, a knife blade storable within the body and one or more magnets coupled to the body and a base comprising a magnetically attractive surface and for removably coupling with the magnets of the utility knife. In some embodiments, the one or more magnets are embedded within and raised from an exterior of the body. In further embodiments, the one or more magnets are embedded within an adapter that removably couples with the body. In some embodiments, the knife blade folds out from a side of the body and into an operable position. In further embodiments, the blade slides out from a top of the body and into an operable position. In some embodiments, a shape of the one or more magnets is selected from a set comprising a strip, a ball bearing and a disc. In further embodiments, at least one of the one or more magnets comprise one or more of a neodymium magnet and a ceramic magnet. In some embodiments, the one or more magnets and the base are configured with interlocking geometry. In further embodiments, the one or more magnets are embedded within a raised surface of the body.

In a further aspect, a method of assembling a utility knife comprises providing a utility knife body, coupling a knife blade to the utility knife body, wherein the knife blade is storable within the body, and coupling one or more magnets to the body. In some embodiments, the one or more magnets are embedded within and raised from an exterior of the body. In further embodiments, the one or more magnets are embedded within an adapter that removably couples with the body. In some embodiments, the knife blade folds out from a side of the body and into an operable position. In further embodiments, the blade slides out from a top of the body and into an operable position.

BRIEF DESCRIPTION OF THE DRAWINGS

FIG. 1 illustrates a front view of a utility knife comprising one or more magnets in accordance with some embodiments.

FIG. 2 illustrates a side view of a utility knife comprising one or more magnets in accordance with some embodiments.

FIGS. 3A and 3B illustrate an adapter for a utility knife and comprising one or more magnets in accordance with some embodiments.

FIG. 4 illustrates a side view of a utility knife coupled with an adapter comprising one or more magnets in accordance with some embodiments.

FIG. 5A illustrates a front view of a utility knife comprising one or more magnets in accordance with some embodiments.

FIG. 5B illustrates a utility knife coupled with an adapter comprising one or more magnets in accordance with some embodiments.

FIG. 6A illustrates a front view of a base for a utility knife in accordance with some embodiments.

FIG. 6B illustrates a back view of a base for a utility knife in accordance with some embodiments.

FIGS. 7A and 7B illustrate a utility knife coupled with a base in accordance with some embodiments.

FIGS. 8A and 8B illustrate a utility knife coupled with a base in accordance with some embodiments.

FIG. 9 illustrates a method of assembling a utility knife in accordance with some embodiments.

DETAILED DESCRIPTION OF THE INVENTION

In the following description, numerous details are set forth for purpose of explanation. However, one of ordinary skill in the art will realize that the invention may be practiced without the use of these specific details or with equivalent alternatives. Thus, the presently claimed invention is not intended to be limited to the embodiments shown but is to be accorded the widest scope consistent with the principles and features described herein. Throughout the description similar components are similarly marked in order to aid comprehension.

Embodiments of the invention are directed to a utility knife comprising a knife blade storable within the body and one or more magnets coupled to the body. The utility knife is configured to removably couple with a securing base. The securing base comprises a magnetically attractive surface for removably coupling with the one or more magnets of the body. The securing base secures the utility knife in a convenient location when the utility knife is not being used. The utility knife is able to couple with the securing base in a vertical orientation and a horizontal orientation. The securing base is able to removably attach to an additional object such as the user's belt. Alternatively, the securing base is able to mount to an additional object such as a wall or tool box.

Referring now to FIG. 1, a utility knife is shown therein. The utility knife 100 comprises a body 101, a knife blade 103 stored within the body, and one or more magnets 105 coupled to the body 101. In some embodiments, the utility knife 100 also comprises a lock release 109 and a hanging mechanism 111. The knife blade 103 is folded out from a side of the body 101 and into the operable cutting position. In some embodiments when the knife blade 103 is placed in the operable position it is locked and the lock release 109 must be depressed in order to fold the knife blade 103 back into the body and place it in the stored state.

In some embodiments, the one or more magnets 105 are embedded within and raised from an exterior of the body 101. In some embodiments, the one or more magnets 105 are embedded within and raised from a raised surface 107 of the body 101. Particularly, the one or more magnets 105 are embedded within a surface of the body 101 such that a portion of the one or magnets 105 is above and below the surface. For example, in some embodiments, the one or more magnets 105 are attached to the body 101 and the surface of the utility knife 100 is molded and/or manufactured around the one or more magnets 105. In some embodiments, the one or more magnets 105 are embedded within a plastic surface of the body 101. Alternatively, the one or more magnets 105 are embedded within a rubberized surface of the body 101. As will be apparent to someone of ordinary skill in the art, the one or more magnets 109 are able to be embedded in any portion of the body 101 of the utility knife 100. In some embodiments, the raised surface 107 and the one or more magnets 105 attach to the body 101 by one or more screws 113 in a top and/or a bottom of the raised surface 107 and the body 101. In some embodiments, the body 101 comprises molded EVA plastic. In some embodiments, the body 101 comprises one or more of metal, steel, plastic or a combination thereof. However, as will be apparent to someone of ordinary skill in the art, the body 101 is able to be manufactured in any appropriate configuration.

In some embodiments, at least one of the one or more magnets 105 comprises a neodymium magnet or a ceramic magnet. As will be evident to someone of ordinary skill in the art, the utility knife 100 is able to comprise any number and combination of magnets. For example, in some embodiments, the utility knife 100 comprises a plurality of magnets. In some embodiments, a shape of the one or more magnets 105 are selected from a set comprising a strip, a ball bearing and a disc.

10 The one or more magnets 105 of the utility knife 100 enable a user to removably couple the utility knife with a magnetically attractive surface when the utility knife 100 is not being used. For example, a user is able to removably couple the utility knife 100 with a nearby surface in order to free up space and remove clutter, while still keeping the utility knife 100 nearby. In some embodiments, a user is able to removably couple the utility knife 100 with a universal base such as described below.

FIG. 2 illustrates a side view of a utility knife comprising one or more magnets in accordance with some embodiments. The utility knife 200 comprises a body 201, a storable knife blade and one or more magnets 205 coupled to the body 201. As shown within FIG. 2, the one or more magnets 205 are coupled to the raised surface 207. In some embodiments, the one or more magnets 205 are embedded within the raised surface 207 such that a portion of each magnet is within the surface 207 and a portion of each magnet juts out from the surface 207. Alternatively, in some embodiments, the one or more magnets 205 are embedded within and raised from an exterior of the body 201. In some embodiments, the one or more magnets 205 are attached to an outside surface of the body 201. In further embodiments, the one or more magnets 205 are coupled to an adapter, which is configured to removably couple with a utility knife.

FIGS. 3A and 3B illustrate an adapter for removably coupling with a utility knife in accordance with some embodiments. The adapter 320 comprises an adapter body 321 and one or more magnets 325 coupled to the body 321. As shown within FIGS. 3A and 3B, the adapter 320 also comprises a through hole 329 for removably coupling with a utility knife. The one or more magnets 325 are shown embedded within and raised from an exterior surface of the body 321. However, the one or more magnets 325 are able to couple with the body 301 in any appropriate manner, as described above. In some embodiments, adapter 320 comprises molded EVA plastic. In some embodiments, the adapter 320 comprises one or more of metal and steel or a combination thereof. However, as will be apparent to someone of ordinary skill in the art, the adapter 320 is able to be manufactured in any appropriate configuration.

In some embodiments, at least one of the one or more magnets 325 comprises a neodymium magnet or a ceramic magnet. As will be evident to someone of ordinary skill in the art, the adapter 320 is able to comprise any number and combination of magnets. For example, in some embodiments, the adapter 320 comprises a plurality of magnets. In some embodiments, a shape of the one or more magnets 325 are selected from a set comprising a strip, a ball bearing and a disc.

FIG. 4 illustrates an adapter removably coupled with a utility knife in accordance with some embodiments. The adapter 420 has been coupled to the utility knife 401 by inserting the clip 415 of the utility knife 401 through the through hole 429 of the adapter 420. When the belt clip 415 is inserted through the through hole 429, the one or more magnets 425 face in an outward direction and away from the body 421 of the utility knife 401. Although the adapter 420

is shown coupled with the clip 415, in some embodiments, the adapter 420 couples with the utility knife 401 by removing the one or more screws 417 and screwing the adapter to the utility knife 401. As will be apparent to someone of ordinary skill in the art, the adapter 420 is able to couple with the utility knife 401 by any appropriate mechanism as known in the art.

The adapter 420 enables a user to add magnets to a previously non-magnetic utility knife and couple the utility knife with a magnetically attractive surface. Consequently, as described above, a user is able to removably couple the utility knife 100 with a nearby surface in order to free up space and remove clutter, while still keeping the utility knife 100 nearby. In some embodiments, a user is able to removably couple the utility knife 100 with a universal base such as described below.

FIGS. 5A and 5B illustrate a utility knife comprising one or more magnets in accordance with some embodiments.

As shown in FIG. 5A, the utility knife 500 comprises a body 501, a knife blade 503 storable within the body 501, and one or more magnets 505 coupled to the body 501. In order to move the knife blade 503 to the extended and operable position, the button 519 is depressed and slid upward in order to slidably push the blade 503 out from a top of the body 501. In some embodiments, when the knife blade 503 is slid to the operable position it is locked into place and the button 519 must be depressed in order to unlock the blade 503 and slide it back down in order to store the blade 503 within the body 501.

In some embodiments, the one or more magnets 505 are embedded within and raised from an exterior of the body 501. In some embodiments, the one or more magnets 505 are embedded within and raised from a raised surface 507 of the body 501. Particularly, the one or more magnets 505 are embedded within a surface of the body 501 such that a portion of the one or magnets 505 is above and below the surface. For example, in some embodiments, the one or more magnets 505 are attached to the body 501 and the surface of the utility knife 500 is molded and/or manufactured around the one or more magnets 505. In some embodiments, the one or more magnets 505 are embedded within a plastic surface of the body 501. Alternatively, the one or more magnets 505 are embedded within a rubberized surface of the body 501. As will be apparent to someone of ordinary skill in the art, the one or more magnets 505 are able to be embedded in any portion of the body 501 of the utility knife 500. In some embodiments, the raised surface 507 and the one or more magnets 505 attach to the body 501 by one or more screws 513 in a top and/or a bottom of the raised surface 507 and the body 501. In some embodiments, the body 501 comprises molded EVA plastic. In some embodiments, the body 501 comprises one or more of metal and steel or a combination thereof. However, as will be apparent to someone of ordinary skill in the art, the body 501 is able to be manufactured in any appropriate configuration.

In some embodiments, at least one of the one or more magnets 505 comprises a neodymium magnet or a ceramic magnet. As will be evident to someone of ordinary skill in the art, the utility knife 500 is able to comprise any number and combination of magnets. For example, in some embodiments, the utility knife 500 comprises a plurality of magnets. In some embodiments, a shape of the one or more magnets 505 is selected from a set comprising a strip, a ball bearing and a disc.

FIG. 5B illustrates an adapter, such as described above, removably coupled with a utility knife such as shown in FIG. 5A. The adapter 520 has been coupled to the utility

knife 500 by inserting the clip 515 of the utility knife 500 through the through hole 529 of the adapter 520. When the belt clip 515 is inserted through the through hole 529, the one or more magnets 525 face in an outward direction and away from the body 521 of the utility knife 500. Although the adapter 520 is shown coupled with the clip 515, in some embodiments, the adapter 520 couples with the utility knife 500 by removing the one or more screws 517 and screwing the adapter to the utility knife 500. As will be apparent to someone of ordinary skill in the art, the adapter 520 is able to couple with the utility knife 500 by any appropriate mechanism as known in the art.

The adapter 520 comprises an adapter body 521 and one or more magnets 525 coupled to the body 521. As shown within FIGS. 5A and 5B, the adapter 520 also comprises a through hole 529 for removably coupling with a utility knife. The one or more magnets 525 are shown embedded within and raised from an exterior surface of the body 521. However, the one or more magnets 525 are able to couple with the body 501 in any appropriate manner, as described above. In some embodiments, adapter 520 comprises molded EVA plastic. In some embodiments, the adapter 520 comprises one or more of metal and steel or a combination thereof. However, as will be apparent to someone of ordinary skill in the art, the adapter 520 is able to be manufactured in any appropriate configuration.

In some embodiments, at least one of the one or more magnets 525 comprises a neodymium magnet or a ceramic magnet. As will be evident to someone of ordinary skill in the art, the adapter 520 is able to comprise any number and combination of magnets. For example, in some embodiments, the adapter 520 comprises a plurality of magnets. In some embodiments, a shape of the one or more magnets 525 are selected from a set comprising a strip, a ball bearing and a disc.

FIGS. 6A and 6B illustrate a base for securing a utility knife in accordance with some embodiments. In some embodiments, the base is the same as the universal base as described in the co-owned U.S. patent application Ser. No. 13/379,702, which is hereby incorporated by reference. The base 630 comprises a surface 635, a binding 637, a magnetically attractive surface 631, and one or more securing corners 633. As shown in FIG. 6A, the base 630 comprises a +-shaped magnetically attractive surface and a plurality of plastic securing corners together forming a rectangular shape. In some embodiments, the magnetically attractive surface 631 comprises a metal surface and the one or more securing corners 633 comprise a plastic material. The one or more securing corners 633 secure the utility knife when it is coupled with the base 630. In some embodiments, the utility knife is securable in a vertical orientation and a horizontal orientation.

FIG. 6B shows a back view of a securing base 630 in accordance with some embodiments. In some embodiments, the securing base 630 comprises a clip 639 for removably coupling with an additional article such as a belt. However, the universal base 630 is able to couple with an additional article by any mechanism as known in the art. For example, in some embodiments, the universal base 630 couples to an additional article by one or more of magnets and a hook and loop fastening system. In some embodiments, the securing base 630 is mountable to an additional object.

FIGS. 7A and 7B illustrate the operation of the base for securing a utility knife with a knife blade that it is folded out from a side of the body and into the operable cutting position.

The base 730 comprises a surface 735, a binding 737, a magnetically attractive surface 731, and one or more securing corners 733. When the base 730 is coupled with an additional item such as a belt, the magnetically attractive surface 731 and the one or more securing corners 733 face outward. A user is able to removably couple the one or more magnets of a utility and/or an adapter with the magnetically attractive surface 731. As shown within FIG. 7A, the utility knife 700 is removably coupled with the base 730 and secured in a horizontal orientation. In some embodiments, the base 730 comprises a +-shaped magnetically attractive surface and a plurality of plastic securing corners together forming a rectangular shape. Accordingly, when the utility knife 700 is coupled to the base 730 and secured in a horizontal orientation the one or more magnets of the utility knife are in a center of the magnetically attractive surface 731 and a top end and a bottom end of the utility knife 700 extend through an open space on the left side and the right side of the magnetically attractive surface 731 and in between the one or more securing corners 733. Similarly, in FIG. 7B, the utility knife 700 is removably coupled with the base 730 and secured in a vertical orientation. When the utility knife 700 is coupled to the base 730 and secured in a vertical orientation the one or more magnets of the utility knife 700 are in a center of the magnetically attractive surface 731 and a top end and a bottom end of the utility knife 700 extend through an open space on the top side and the bottom side of the magnetically attractive surface 731 and in between the one or more securing corners 733. As described above, in some embodiments, the base 730 comprises a single securing edge that completely surrounds the magnetically attractive surface 731. In these embodiments, the one or more magnets are secured in a center of the securing edge in a horizontal or a vertical orientation and the top end and bottom end of the utility knife 700 extend above the securing edge.

When the utility knife 700 is removably coupled with the base 730, the utility knife 700 is securely held in place and prevented from moving in a horizontal or a vertical direction by the interaction of the one or more magnets with the magnetically attractive surface 731 and the one or more securing corners 733. In some embodiments, the utility knife 700 and the base 730 comprise interlocking geometry. For example, in some embodiments, when the utility knife 700 is coupled with the base 730, the one or more magnets removably couple with the magnetically attractive surface 731 and the raised surface of the body 701 is held by the one or more securing corners 733. Consequently, when the utility knife 700 is removably coupled with the base 730, the utility knife 700, is secured by two separate mechanisms. Thus, in order to remove the utility knife 700 from the base 730, the one or more magnets are removed from the magnetically attractive surface 731 and the utility knife 700 is separated from the one or more securing corners 733.

FIGS. 8A and 8B illustrate the operation of the base for securing a utility knife comprising a button that it is slid upward in order to slidably push the blade out from a top of the body and into the operable cutting position.

The base 830 comprises a surface 835, a binding 837, a magnetically attractive surface 831, and one or more securing corners 833. When the base 830 is coupled with an additional item such as a belt, the magnetically attractive surface 831 and the one or more securing corners 833 face outward. A user is able to removably couple the one or more magnets of a utility and/or an adapter with the magnetically attractive surface 831. As shown within FIG. 8A, the utility knife 800 is removably coupled with the base 830 and

secured in a horizontal orientation. As described above, in some embodiments, the one or more securing corners 833 are each located at a corner of the magnetically attractive surface 831. Accordingly, when the utility knife 800 is coupled to the base 830 and secured in a horizontal orientation the one or more magnets of the utility knife are in a center of the magnetically attractive surface 831 and a top end and a bottom end of the utility knife 800 extend through an open space on the left side and the right side of the magnetically attractive surface 831 and in between the one or more securing corners 833. Similarly, in FIG. 8B, the utility knife 800 is removably coupled with the base 830 and secured in a vertical orientation. When the utility knife 800 is coupled to the base 830 and secured in a vertical orientation the one or more magnets of the utility knife 800 are in a center of the magnetically attractive surface 831 and a top end and a bottom end of the utility knife 800 extend through an open space on the top side and the bottom side of the magnetically attractive surface 831 and in between the one or more securing corners 833. As described above, in some embodiments, the base 830 comprises a single securing edge that completely surrounds the magnetically attractive surface 831. In these embodiments, the one or more magnets are secured in a center of the securing edge in a horizontal or a vertical orientation and the top end and bottom end of the utility knife 800 extend above the securing edge.

When the utility knife 800 is removably coupled with the base 830, the utility knife 800 is securely held in place and prevented from moving in a horizontal or a vertical direction by the interaction of the one or more magnets with the magnetically attractive surface 831 and the one or more securing edges. In some embodiments, the utility knife 800 and the base 830 comprise interlocking geometry. For example, in some embodiments, when the utility knife 800 is coupled with the base 830, the one or more magnets removably couple with the magnetically attractive surface 831 and the raised surface of the body 801 is held by the one or more securing edges 833. Consequently, when the utility knife 800 is removably coupled with the base 830, the utility knife 800, is secured by two separate mechanisms. Thus, in order to remove the utility knife 800 from the base 830, the one or more magnets are removed from the magnetically attractive surface 831 and the utility knife 800 is separated from the one or more securing corners 833.

When using the utility knife, a user is able to couple the utility knife with a magnetically attractive surface. For example, the user is able to couple the utility knife with the magnetically attractive surface by using the one or more magnets of the utility knife. Alternatively, a user first couples an adapter to the utility knife and couples the utility knife with the magnetically attractive surface by using the one or more magnets of the adapter. This enables a user to removably couple the utility knife with a variety of items including a tool box, steel beam, or other magnetically attractive surface. Alternatively, the utility knife removably couples with a base which is clipped or attached to another object. In either case, a user is able to keep the utility knife in a known place and within close reach while working. Additionally, because in some embodiments, the one or more magnets are embedded within and raised from an exterior surface of the body, the utility knife is able to securely attach to a magnetically attractive surface without interference from the body or other aspect of the utility knife. Moreover, because the one or more magnets are molded into and/or embedded within the body, powerful neodymium and/or

ceramic magnets are able to be used in order to securely hold and couple the utility knife with the magnetically attractive surface.

FIG. 9 illustrates a method for assembling a utility knife in accordance with some embodiments. The method begins in the step 910. In the step 920, a utility knife body is provided. In the step 930, a knife blade is coupled to the body. The knife blade is storable within the utility knife body. In some embodiments, the knife blade is coupled with the body such that it is folded out from a side of the body and into the operable cutting position. In some embodiments, the knife blade is coupled with the body such that it is slid upward in order to slidably push the blade out from a top of the body and into the operable position. In the step 940 one or more magnets are coupled to the utility knife body. In some embodiments, the one or more magnets are embedded within and raised from an exterior of the body. Alternatively, in some embodiments, the one or more magnets are embedded within an adapter that removably couples with the body. The one or more magnets of the utility knife enable a user to removably couple the utility knife with a magnetically attractive surface and/or a base with a magnetically attractive surface when the utility knife is not being used. For example, a user is able to removably couple the utility knife with a nearby magnetically attractive surface in order to free up space and remove clutter, while still keeping the utility knife nearby. In the step 950, the method ends.

Using a utility knife comprising magnets in conjunction with the base enables a user to keep the utility knife near to the user for easy access and use. For example, a user is able to clip the base to the user's belt and secure the utility knife in a horizontal or a vertical configuration. Then, when the utility knife is needed it is removed from the base without an unneeded search and without having to move from the workspace. Particularly, the magnetic utility knife and holder enables a user to freely complete a work project without misplacing the utility knife cluttering the work area. Further, because the utility knife is coupled to the base in a horizontal or vertical orientation, the user is able to secure the utility knife in the most comfortable and convenient manner.

When the utility knife is coupled with the base, the utility knife is closely and securely held a by two separate mechanisms. In one instance, the utility knife is securely held by the base due to the attraction of the one or more magnets of the holder with a magnetically attractive surface of the base. As described above, in some embodiments, the utility knife is also secured by the interlocking geometry of the body and the base. Further, by incorporating magnets directly with an outer body of the utility knife, it is able to couple with a magnetically attractive surface without additional modification. Alternatively, if the utility knife does not incorporate magnets, the utility knife is able to be coupled with an adapter incorporating magnets within its outer body and then coupled with a magnetically attractive surface. Thus, the magnetic utility knife and holder and outer body as described above have many advantages.

The invention has been described in terms of specific embodiments incorporating details to facilitate the understanding of the principles of construction and operation of the invention. Such reference herein to specific embodiments and details thereof is not intended to limit the scope of the claims appended hereto. It will be apparent to those skilled in the art that modifications are able to be made in the embodiment chosen for illustration without departing from the spirit and scope of the invention. Specifically, it will be apparent that the design for the utility knife and

holder is able to be implemented with many different tool holders as known in the art. Further, it will be apparent to one of ordinary skill in the art that the precise structure of the device is able to be substantially varied to accommodate various magnetically attractive materials and configurations of magnets. Consequently, the claims should be broadly construed, consistent with the spirit and scope of the invention, and should not be limited to their exact, literal meaning.

10

I claim:

1. A utility knife in combination with a base, The utility knife comprising:

- a. a body;
- b. an elongated raised surface extending from a side of the body;
- c. a knife blade storable within the body; and
- d. one or more body magnets embedded within and raised from the elongated raised surface extending from the side of the body;

the base comprising a +-shaped magnetically attractive surface and a plurality of plastic corners together forming a rectangular shape, wherein the one or more body magnets of the utility knife are able to removably couple with the +-shaped magnetically attractive surface thereby allowing the utility knife to removably couple with the base.

2. The utility knife of claim 1 wherein the knife blade folds out from a side of the body and into an operable position.

3. The utility knife of claim 1 wherein the knife blade slides out from a top of the body and into an operable position.

4. The utility knife of claim 1 wherein a shape of the one or more body magnets comprises a disc.

5. The utility knife of claim 1 wherein at least one of the one or more body magnets comprise one or more of a neodymium magnet and a ceramic magnet.

6. The utility knife of claim 1 wherein the body comprises a first end and a second end which extend beyond the +-shaped magnetically attractive surface when the utility knife is coupled to the base.

7. A system for securing a utility knife comprising:

- a. a utility knife comprising:
  - i. a body;
  - ii. an elongated raised surface extending from a side of the body;
  - iii. a knife blade storable within the body; and
  - iv. one or more body magnets embedded within the elongated raised surface extending from the side of the body; and
- b. a base comprising a +-shaped magnetically attractive surface and a plurality of plastic securing corners together forming a rectangular shape, wherein the one or more body magnets of the utility knife are able to be removably coupled with the +-shaped magnetically attractive surface.

8. The system of claim 7 wherein the knife blade folds out from a side of the body and into an operable position.

9. The system of claim 7 wherein the knife blade slides out from a top of the body and into an operable position.

10. The system of claim 7 wherein a shape of the one or more body magnets comprises a disc.

11. The system of claim 7 wherein at least one of the one or more body magnets comprise one or more of a neodymium magnet and a ceramic magnet.

12. The system of claim 7 wherein the body comprises a first end and a second end which extend beyond the

25

11

+-shaped magnetically attractive surface when the one or more body magnets are coupled to the +-shaped magnetically attractive surface.

13. A method of assembling a utility knife and base comprising:

- a. providing a utility knife body;
- b. coupling an elongated raised surface with the body, wherein the elongated raised surface extends from the body;
- c. coupling a knife blade to the utility knife body, wherein the knife blade is storable within the body;
- d. embedding one or more body magnets within the elongated raised surface of the body, wherein the one or more body magnets are embedded within and raised from the elongated raised surface to extend from the side of the body; and
- e. removably coupling the utility knife to the base which comprises a +-shaped magnetically attractive surface

5

12

and a plurality of plastic securing corners together forming a rectangular shape, wherein the one or more body magnets of the utility knife are able to be removably coupled with the +-shaped magnetically attractive surface.

14. The method of claim **13** wherein the knife blade folds out from a side of the utility knife body and into an operable position.

15. The method of claim **13** wherein the knife blade slides out from a top of the body and into an operable position.

16. The method of claim **13** wherein the utility knife body comprises a first end and a second end which extend beyond the +-shaped magnetically attractive surface when the one or more body magnets are coupled to the +-shaped magnetically attractive surface.
